CASTER

Walter F. Herold, Bridgeport, Conn., assignor to
 The Bassick Company, Bridgeport, Conn., a
 corporation of Connecticut

Application September 7, 1935, Serial No. 39,541

2 Claims. (Cl. 16—18)

The present invention relates to an improvement in casters, particularly for office chair use. An object of the invention being to provide a caster having a protecting guard so arranged as 5 to protect the shoe of any one sitting in the chair against contact with the sharp edges of the caster or chair leg. It has been found that in office chairs in which the legs were formed of steel tubing, and particularly stenographers' chairs, that, 10 due to the relatively small dimensions of the legs, the casters projected to such a degree that the occupant of the chair was apt to knock the heels of her shoe against the sharp edges of the caster, and as the heels of women's shoes are usually provided 15 with thin delicate covering materials the shoes were apt to become scuffed and damaged. It is therefore proposed in the present invention to provide a guard which will enclose the sharp edges of the caster, and at the same time will provide a projected surface entirely free of any sharp 20 edges and against which the shoes may be engaged without damage. A further object is to provide a guard which will not interfere with the operation of the caster and which will provide an attractive finish to the end of the chair leg.

25 With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a side elevation of a caster according to the exemplary illustrated embodiment of the invention, the same being shown inserted in the leg end, and a portion of a shoe being shown in dot-and-dash lines in contact therewith.

Fig. 2 is a front elevation of the caster removed from the leg.

40 Fig. 3 is a top plan view.

Fig. 4 is a vertical sectional view.

Similar reference characters indicate corresponding parts throughout the several figures of the drawing.

45 Referring to the drawing, the caster, according to the exemplary illustrated embodiment of the invention comprises a horn 10 supporting an axle 11 upon which the caster wheel 12 is rotatably engaged. The top of the horn is provided with a centrally disposed aperture 13 through which the stud 14 at the lower end of the pintle 15 is engaged and secured by being headed over, as at 16, the pintle being provided at its base above the horn top with a flange 17. The guard 18 is of substantially bell-shape and is provided centrally in its

upper side with an aperture 19. The guard is mounted upon the upper side of the horn and is rigidly secured thereto, during the assembly of the pintle with the horn, by inserting the stud 14 of the pintle through the aperture 19 of the guard 5 and through the aperture 13 of the horn, the stud being then headed over at 16 as above pointed out. The guard extends downwardly and outwardly about the horn and at its forward side is provided with a cut-out 20 in which the tread of 10 the wheel 12 engages. The projected surface of the guard is rounded, as at 21, and the lower edge is curled inwardly.

In the assembled relation of the caster with the 15 chair leg 22, as shown in Fig. 1, the guard completely encloses or guards the edges of the caster horn. At the same time the rounded surface 21 is entirely free of any sharp edges there is no chance of the shoe becoming scuffed or otherwise damaged through contact therewith. At the forward side, where the wheel projects, the wheel 20 will prevent the shoe from coming in contact with the guard, but as the wheel is also free of any sharp edges the shoe will not be damaged through contact with it.

I have illustrated and described a preferred 25 and satisfactory embodiment of my invention, but it will be obvious that changes may be made therein, within the spirit and scope thereof, as defined in the appended claims.

Having thus described my invention what I 30 claim and desire to secure by Letters Patent is:—

1. In a caster, a horn having a vertical swiveling axis and having a top and sides, a wheel carried by said horn sides having a horizontal axis 35 laterally offset with respect to said vertical swiveling axis, and a guard secured to said horn top and projecting outwardly and downwardly in surrounding relation thereto below the top of the wheel, the lower edge of said guard being curved 40 inwardly and disposed in a circumferential line intersecting said wheel in inwardly spaced relation to the wheel tread and having a cut-out engaged by the wheel tread, whereby said wheel projects with respect to one side of said horn top 45 to constitute an obstruction against contact therewith and said guard constitutes a continuous circumferential projection from one side surface of said wheel to the other side surface.

2. In a caster, a horn having a vertical swiveling axis and having a top and sides, a wheel carried by said horn sides having a horizontal axis laterally offset with respect to said vertical swiveling axis, and a guard secured to said horn top and projecting outwardly and downwardly in sur- 55

rounding relation thereto below the top of the wheel, the lower edge of said guard being disposed in a circumferential line intersecting said wheel in inwardly spaced relation to the wheel tread and having a cut-out engaged by the wheel tread, whereby said wheel projects with respect to one

side of said horn top to constitute an obstruction against contact therewith and said guard constitutes a continuous circumferential projection from one side surface of said wheel to the other side surface.

WALTER F. HEROLD.
